UNITED STATES PATENT OFFICE

93,369

DESIGN FOR A FISH BAIT BODY

Lyell J. Wooster, Dowagiac, Mich., assignor to
James Heddon's Sons, Dowagiac, Mich., a cor-
poration of Michigan

Application May 14, 1934, Serial No. 51,784

Term of patent 14 years

To all whom it may concern:

Be it known that I, LYELL J. WOOSTER, a citizen of the United States, residing at Dowagiac, in the county of Cass and State of Michigan, have invented a new, original, and ornamental Design for a Fish Bait Body, of which the following is a specification, reference being had to the accompanying drawing forming part thereof wherein is illustrated in side elevation a fish bait body showing my new design.

The fish bait body is of conventional form in that it is transversely rounded. The surface ornamentation illustrated in the drawing is duplicated upon the opposite sides of the body.

I claim:

The ornamental design for a fish bait body, as shown and described.

LYELL J. WOOSTER.
